JOSEPH HINDLE, OF ACCRINGTON, ENGLAND

MEANS FOR BRAKING SPINDLES EMPLOYED IN RING SPINNING FRAMES, OR IN OTHER FRAMES IN WHICH SIMILARLY BRAKED SPINDLES ARE USED

Application filed May 2, 1932, Serial No. 608,730, and in Great Britain August 28, 1931.

The invention relates to the braking of spindles employed in ring spinning frames, or similarly braked spindles in other frames, such as ring doubling frames. The object of 5 the invention is to combine with known braking means an improved form of holding-down device for the spindle concerned, said device being simple and effective in use, and readily released. The braking means aforesaid are 10 also adapted for retaining the holding-down device named in the operative position on the one hand, or in the inoperative position, on the other hand, as herein described. Hitherto, the usual holding-down device employed has 15 been one in the form of a pivoted catch, capable of being pushed at its upper end over a part of the spindle, such as over the wharve or small pulley attached to said spindle, and whereby the latter is driven by means of a band passing about such pulley or wharve, as understood. When so engaged by the holding-down device mentioned, the spindle cannot be withdrawn from its mount or bolster, but disengagement from said device enables 20 the same to be withdrawn as desired.

According to my invention, in place of the pivoted catch aforesaid, I employ a holding-down device of a slidable character, or one capable of sliding in a direction across the 25 position of the axis of the spindle, in and out of action.

This device, so capable of lateral movement, passes about the position of the spindle or mount therefor, and is provided with suitable braking material, such as leather, at a 30 part which comes over a portion of the spindle wharve or flange thereof, when the said device is moved into position for holding-down the spindle.

40 The braking member made use of consists of a more or less horizontal portion, when in position relatively to the spindle concerned, and a downwardly projecting or depending part, the latter capable of being pressed by 45 the hand or knee, for example, of the operator, on which occasion, the horizontal part referred to may press against a flange of the spindle wharve for braking purposes, and so stop the spindle revolving. Braking material is provided on a suitable surface of 50

the braking means named, and the improved holding-down device co-operates with said braking means for so braking the spindle, as herein set forth.

For retaining or locking the holding-down device in a given position, a projection from the depending part of the braking means is capable of entering a cavity or slot in the holding-down device, for retaining the latter in the holding-down position, on the other hand said projection may abut against an external part of said holding-down device, for retaining the latter out of action, as herein described.

55 The depending part of the braking means is capable of being pushed either inwardly or outwardly, and a further projection may be included for limiting its movement.

60 In the accompanying drawing, Fig. 1 is a sectional elevation of a portion of a spindle and mount therefor, provided or arranged according to a form of my invention, the parts being in the working position. Fig. 2 is a modification of a part of Fig. 1. Fig. 3 shows a portion of Fig. 1 with parts in different positions.

65 Fig. 4 is a sectional plan view, chiefly of the improved holding-down device, while Fig. 5 is an under-plan view in relation to said Fig. 1, but chiefly concerned with the braking means or member named herein. Figs. 6 and 7 are perspective views, on an enlarged scale, of the improved holding-down device, and a part of the braking member, respectively, and referred to herein. The 70 spindle, which in the present example is one suitable for a ring spinning frame, is shown at 1, its attached wharve being indicated at 2. A part of the machine framing is shown at 3 in Figs. 1 to 3 inclusive, and to which the 75 mount for said spindle is attached in manner indicated, and well known.

80 According to our invention, the holding-down device is shown at 4 in Figs. 1, 3, and 4, as well as in Fig. 6, while a modified form is 85 shown at 5 in Fig. 2. This device is of a slidable nature, or is capable of being moved laterally in a direction across the position of the axis of the spindle 1, when the latter 90 is in its mounted condition, for which slid- 95

ing purpose the device named is provided with a cavity or slot at 6 (Figs. 4 and 6) whereby it is able to pass about a portion 7 of the spindle mount. This slot being elongated, the device 4 in Fig. 1 is capable of being moved to right or left on that part of the mount named. That is to say, the device 4 may be moved to the position shown in Fig. 1, for holding down the spindle 1, or, alternatively, moved to the position indicated in Fig. 3.

A bent-over portion of the device 4 is provided with braking material, such as leather, at 8, which bent-over portion is seen in Fig. 1 to pass above a flange of the wharve 2 at the rear part of the spindle 1. In such a position, the bent-over part named prevents the spindle 1 being withdrawn from the mount for it. But when slid laterally to the left from said position, so as to be situated as in Fig. 3, the holding-down device releases the spindle, or allows it to be lifted out of its mount. A braking member is shown at 9, with a depending part at 10 for being pressed by the operator either towards or away from the position of the mounted spindle, as the case may be. Such member 9 is slotted or formed with a cavity at 11 (Figs. 5 and 7) to enable said member to pass about the portion 7 of the spindle mount. This braking member is loosely situated about the part such as 7, and normally rests upon the surface of the holding-down device, the latter resting upon the surface of the framing 3.

Braking material, such as leather, is indicated at 12 for the member 9 aforesaid. It will be seen that this material comes adjacent to a lower flange of the wharve 2, so that when the depending part 10 of member 9 is pressed inwards or towards the position of spindle 1, the material 12 comes against the flange last referred to, and the wharve 2 and spindle 1 are slightly raised thus making contact take place between the upper flange of said wharve and material 8 on the bent-over or catch portion of the device 4. In this way the spindle is braked.

On a reverse movement of the depending part 10 of the braking member, the position shown in Fig. 1 may be attained, or re-established, and the spindle be in motion again. But if the reverse movement mentioned be continued until the position shown in Fig. 3 is reached, the holding-down device may be pushed out of action as there indicated, thus releasing the spindle 1. For retaining the holding-down device 4 in the position shown in Fig. 1, a projection 13 from member 9 enters the slot or cavity 6 in the device 4 named, and so prevents the latter being accidentally shaken or moved to the position such as illustrated in Fig. 3.

But when the projection 13 is disengaged from the device 4, then said device may be

moved out of action to a position as in Fig. 3 aforesaid.

The wedge shape of the projection here used tends to draw the device 4 to the right in Fig. 1 at the moment of engagement, between said projection and the cavity or slot 6, by pressure against the front edge of said slot, as will be obvious.

It will also be seen that if the member 9 is dropped to the position of it in Fig. 1 when the holding-down device 4 is out of action, as in Fig. 3, then the projection 13 aforesaid operates to prevent the return of the device 4 to the position in said Fig. 1.

A further projection 14 from the depending portion 10 of the braking member 9 is shown in Figs. 1, 2, 3, 5 and 7, and which further projection may be used to limit the extent of upward movement of said member 9 when the end of device 4 comes between said projection and the one marked 13 before referred to. It is seen that the means of engagement between projection 13 and cavity 6 is by way of example, and a projection entering a cavity for engagement purposes is what is aimed at.

Likewise the engagement of the holding-down device with the part 7 of the spindle mount is merely an example of how this might be attained.

In Figs. 4 and 5 the clearances between mount-part 7 and the sides of the slots in parts 4 and 9 are somewhat exaggerated.

In Fig. 2 the catch portion of a holding-down device 5 comes over the bottom flange of the wharve 2, and the braking is wholly applied to said flange, but not necessarily so.

With the exception of the provided projections such as 13 and 14, the braking member shown herein may be said to be very similar to ordinary braking members in use; but from what has been described it will be seen that the laterally slideable holding-down device mounted about the axis of the spindle concerned, and the braking member which is tilted as illustrated for being put into operation, co-operate for applying brake pressure to the spindle involved.

I claim:

1. Means for braking spindles employed in ring spinning frames, or in other frames in which similarly braked spindles are used, comprising a spindle, a holding-down device for said spindle, slidably mounted about the axis thereof, for being laterally moved in and out of action in directions across the position of the axis of said spindle, a braking member loosely mounted about the axis of said spindle, and adjacent to said holding-down device, for being tilted in order to brake the spindle aforesaid, said holding-down device and said braking member co-operating in the braking operation, as herein set forth.

2. Means for braking spindles employed

in ring spinning frames, or in other frames in which similarly braked spindles are used, comprising a spindle, a holding-down device for said spindle, slidably mounted about the axis thereof, for being laterally moved in and out of action in directions across the position of the axis of said spindle, a braking member loosely mounted about the axis of said spindle, and adjacent to said holding-down device, for being tilted in order to brake the spindle aforesaid, a part of said braking member for engaging a part of the holding-down device when the latter is in the holding-down position, a part of the holding-down device aforesaid for being so engaged, said holding-down device and said braking member co-operating in the braking operation, as herein set forth.

3. Means for braking spindles employed in ring spinning frames, or in other frames in which similarly braked spindles are used, comprising a spindle, a holding-down device for said spindle, slidably mounted about the axis thereof, for being laterally moved in and out of action in directions across the position of the axis of said spindle, a braking member loosely mounted about the axis of the spindle aforesaid, and adjacent to said holding-down device, for being tilted in order to brake the spindle named, a projection on said braking member for limiting the upward movement of the latter when the holding-down device is in the holding-down position, said holding-down device and said braking member co-operating in the braking operation, as herein set forth.

4. Means for braking spindles employed in ring spinning frames, or in other frames in which similarly braked spindles are used, comprising a spindle, a slotted holding-down device for said spindle, slidably mounted about a portion of the spindle mount, by said mount portion passing through said slot, said holding-down device laterally moved in and out of action in directions across the position of the spindle axis, a slotted braking member loosely mounted at said slot about the portion of spindle-mount aforesaid, and adjacent to said holding-down device, for being tilted in order to brake the spindle named, and for being disengaged from said holding-down device, alternatively, a projection on said braking member for engaging the slot in the holding-down device when the latter is in the holding-down position, and for preventing re-engagement of the latter when the same is out of action, a second projection on the braking member, for limiting the upward movement of the latter when the holding-down device is in the holding-down position, said holding-down device and said braking member co-operating in the braking operation, as herein set forth.

JOSEPH HINDLE.
